CLAIM

The ornamental design for a shoe upper, as shown and described.

DESCRIPTION

FIG. 1 is a right side elevational view of a shoe upper showing our new design. The broken line showing of a shoe sole is for environmental purposes only and forms no part of the claimed design;

FIG. 2 is a top plan view thereof;

FIG. 3 is a bottom plan view thereof;

FIG. 4 is a left side elevational view thereof;

FIG. 5 is a front elevational view thereof; and

FIG. 6 is a rear elevational view.

UNITED STATES PATENT AND TRADEMARK OFFICE
CERTIFICATE OF CORRECTION

PATENT NO. : D299,081

DATED : December 27, 1988

INVENTOR(S) : PATRICIA D. QUAN, ANGELO MACCANO & ROBERT Y. GREENBERG

It is certified that error appears in the above-identified patent and that said Letters Patent is hereby corrected as shown below:

Title page in the identification of the inventors add the following:

-- Angelo Maccano, Simi Valley, California and Patricia D. Quan, Hermosa Beach, California.

Title page in the references cited add the following:
